RIFLE GRENADE

Edgar William Brandt, Geneva, Switzerland, assignor to Societe Anonyme Belge de Mecanique et d'Armement, Brussels, Belgium, a corporation of Belgium

Application August 17, 1953, Serial No. 374,532

Claims priority, application Luxembourg
September 15, 1952

2 Claims. (Cl. 102—65.2)

This invention relates to a rifle grenade of the hollow charge type, provided with a base fuze.

Existing hollow charge projectiles are equipped either with a head fuze in which the transmission of fire is effected through the hood, or perforating cone open at its apex, to a detonator housed in the explosive charge, or with a base fuze operating by inertia on impact on the target and disposed behind the perforating cone, the apex of which is then closed.

Nevertheless, apart from their inferior properties as regards instantaneity of operation, fuzes of the second type had hitherto disadvantages both from the point of view of their sensitivity, and as regards their safety and the regularity of their operation.

Existing base fuzes were in fact provided with an inadequate safety device consisting of a pin, which is drawn out by hand at the moment of action and which consequently considerably slowed down the rate of fire. Devices of this type furthermore impaired the tightness of projectiles. Moreover, in the form in which they were constructed, the accidental explosion of a base detonator invariably entailed the explosion of the projectile.

The present invention aims at obviating the aforementioned disadvantages, but also at providing a base fuze of great sensitivity, proof against shocks both in the course of transport and handling and in the event of the projectile being dropped on its head or on its tail, and in which the accidental explosion of the detonator, for any accidental reason, cannot effect the explosion of the explosive charge.

The rifle grenade of the present invention is fired with the aid of a launcher fixed at the end of the weapon. Said grenade comprises a hollow explosive charge inside a charge carrier body, the cavity of said charge being lined with a metallic cone, a finned tail at the rear of said body stabilizing the grenade on its trajectory, a base fuze functioning by inertia, and a delayed arming safety device.

The characteristic feature of the invention is that said fuze is housed in an intermediate chamber disposed between the charge carrier body and the tail of the grenade, the safety device retaining the detonator, before arming, in said chamber in the inoperative position and outside the charge, the detonator being adapted to pass, after the firing of the shot and under the effect of positive acceleration freeing the safety device, into the operative position in a hollow in the explosive charge which is provided for the purpose and at the bottom of which a striker is rigidly held, a spacing member interposed between the detonator and said striker causing the latter to yield on impact.

Rifle grenades corresponding to this construction may then be transported and handled in full safety, their detonator being in the inoperative position. It is no longer necessary to perform any manual operation in order to arm the fuze, since the arming device remains locked not only up to the moment of firing, but also for a certain distance after the firing of the shot, being then auto-

2

matically released and thus providing effective muzzle safety, preventing the explosion of the projectile in the event of its hitting an obstacle before that distance has been passed.

In one embodiment of the invention, said intermediate chamber has an extension projecting into the tail of the projectile and adapted to penetrate inside the firing tube when the grenade is placed in position at the time of firing. A considerable reduction of the size of the base fuze is obtained in this manner.

According to another feature, the extension of said chamber has at its rear part an increased wall thickness provided to withstand the effects of shock which may be produced under the action of the residues, waste matter, etc. thrown by the gases of the cartridge on to said base.

The spacing member interposed between the detonator and the striker may be either a spring or, for preference, a hollow cylindrical piece the cavity of which widens out from rear to front and is obturated at its greatest aperture by a mat, which first comes into contact with the striker under the action of negative acceleration, and is then perforated by said striker at the moment of impact.

According to a further feature of the invention a cylindrical cushion, constituted by an inert material (paraffin wax, cardboard, flock, or the like) may advantageously be interposed between the striker and the apex of the hood. The result of this construction is that, in the event of the firer inadvertently using a ball cartridge, the grenade can be perforated right through without exploding, since at no point of its path will the ball be in contact with the explosive, and the explosion of the detonator in its position outside the charge cannot entail the explosion of the grenade.

The deferred arming safety device has according to the first modification of the invention an annular inertia member adapted to yield under the effect of positive acceleration against the action of an elastic member bearing against a second inertia member disposed behind the first, the two inertia members then becoming integral with one another by mechanical action (friction, deformation, crimping, interpenetration, and the like), said inertia members sliding towards the front after cessation of the acceleration on the firing of the shot and freeing one or more locking means, for example balls, which can then escape into a suitable housing and permit the passage of the detonator, in the operative position, into the explosive charge of the grenade.

The displacement of the detonator can be effected by counter-acceleration due to the resistance of the air on the projectile, to which action there may if desired be added that of a spring disposed between the detonator and the base of the chamber containing it.

Where desired, the arming of the fuze may be further delayed with the aid of a slide integral with the second inertia member and guided in a zig-zag groove.

According to another modification, the aforesaid inertia members may be concentric, the withdrawal of the first freeing a preliminary locking member, which then permits the forward displacement of the second inertia member.

Alternatively one of the aforesaid inertia members may be omitted, the single inertia member being constrained to perform a reciprocating movement by a fixed slide penetrating into a groove having two branches provided at the periphery of said inertia member.

In the accompanying drawings, given solely by way of example:

Figure 1 is a view with partial axial section of a rifle grenade according to the invention;

Figure 2 shows on a larger scale an axial section of the base fuze of the grenade shown in Figure 1;

Figure 3 is a cross-section on the line 3—3 in Figure 2;

Figure 4 shows a detail of construction of the fuze illustrated in Figure 2;

Figure 5 shows a modified construction of the base fuze;

Figure 6 is a detail of construction of the fuze illustrated in Figure 5;

Figure 7 is a second modification of said fuze;

Figure 8 shows a detail of construction of the fuze shown in Figure 7.

The rifle grenade illustrated in Figure 1 comprises a ballistic cap 1, a body 2, a hollow explosive charge 3 the cavity of which is lined with a metallic cone 4, and a tubular tail 5 carrying at its end stabilizing fins 6. The base fuze of the projectile is housed in an intermediate chamber 7 between the charge carrier body 2 and the tail 5. In the inoperative position the detonator 8 is held in an extension 9 of said chamber projecting into the tubular tail 5, a peripheral space 10 being provided between the wall of the tail 5 and that of the extension 9 in order to permit the penetration of the firing tube 11 (shown in broken lines in Figure 2). The base of the extension 9 has an increased wall thickness 12 adapted to resist the action of the cartridge gases.

In the operative position the detonator 8 is housed in a hollow in the explosive charge, at the bottom of which hollow a striker 14 with its point facing rearwards is held opposite a hollow cylindrical piece 15 obturated at its front end by a mat 16 and placed at the head of the detonator 8, with which it is united. A cylindrical cushion 26, for example of paraffin wax, is interposed between the striker 14 and the apex of the hood 4.

The safety device comprises two annular inertia members, of which, one, 17 is held in the forward position by a spring 18 bearing on the other inertia member 19 which, when at rest, compresses a second spring 20.

The inertia member 17 is provided at its rear part and on its periphery with claws 13 adapted to be crimped, on moving back on the firing of the shot, in an annular groove in the inertia member 19. Two slides 21, held in the inertia member 19, are each guided in a zig-zag groove 22 (Figure 4) in the fixed sleeve 23. Two balls 24 (Figure 3), placed in orifices in the sleeve 22 and diametrically opposed, lock the piece 15 by bearing on an oblique circular bearing surface on the latter and hence lock the detonator 8 which is thus held back of the charge.

In Figure 5 the inertia members 17a and 19a are concentric and the first (17a) under the action of the spring 20a locks in position a ball 25 which locks the second inertia member 19a.

In the embodiment illustrated in Figure 7, a single inertia member 19b is sufficient to effect the locking of the balls 24; its periphery has two grooves 22b, each having two branches. A fixed slide 21b penetrates into each of the grooves, obliging the inertia member to follow the sinuosities of each of said branches.

The functioning of the fuze shown in Figure 2 is as follows:

On the firing of the shot, the inertia member 17 moves backwards during the positive acceleration of the projectile against the action of the spring 18 and its claws

13 are crimped in a peripheral groove in the inertia member 19. The inertia members 17 and 19 which have become attached to one another are then pushed forward by counter-acceleration and under the action of the spring 20, which until that time was compressed. In their displacement, said inertia members follow the sinuosities of the groove 22, guided by the slide 21, while the balls 24 pushed by the piece 15 mounted at the head of the detonator 8 escape. The detonator 8, being freed, passes into the operative position and slides forward by negative acceleration until the striker 14 makes contact with the mat 16.

When the projectile strikes the target the mat 16 bursts and the detonator 8 is thrown on to the striker 14, thereby effecting the explosion of the detonator and that of the explosive charge.

In the embodiment illustrated in Figure 5, the inertia member 17a moves backwards on the firing of the shot, freeing the ball 25, which until that moment had locked the concentric inertia member 19a. The two inertia members then move forwards through counter-acceleration and under the thrust of the spring 20a. The remainder of the operation is the same as previously.

In Figure 7 the inertia member 19b effects alone, by a reciprocating movement, the unlocking of the balls 24, the arming delay being achieved by the action of the slide 21b which obliges the inertia member to follow the sinuosities of each of the branches of the groove 22b.

What is claimed is:

1. A rifle grenade adapted to be fired from a launcher fixed at the end of a firearm, said grenade comprising a charge carrier body, an explosive charge in said carrier body, a vaned tubular tail at the rear of said body to stabilize the grenade on its trajectory, an axial and cylindrical chamber in the rear of said body, the front part of said chamber being in said charge and the rear part of the chamber extending rearwardly an equal distance in said tail, providing a peripheral space between the rear part of said chamber and the internal wall of said tail to receive the end part of said launcher, a striker carried by the front part of said chamber, an inertia base fuse inside said chamber, said fuse including a detonator lodged in the projecting part of said chamber when in inoperative position, and a safety device for retaining the detonator in inoperative position, the total length of said chamber being at least twice the length of said detonator.

2. A rifle grenade as claimed in claim 1, in which the diameter of at least a part of the external wall of said chamber is equal to the internal diameter of said launcher.
